UNITED STATES PATENT OFFICE.

PETER A. ALTMAYER, OF HARRISBURG, PENNSYLVANIA.

MAGAZINE FIRE-ARM.

SPECIFICATION forming part of Letters Patent No. 334,731, dated January 26, 1886.

Application filed September 6, 1884. Serial No. 142,420. (No model.)

To all whom it may concern:

Be it known that I, PETER A. ALTMAYER, of Harrisburg, in the county of Dauphin and State of Pennsylvania, have invented certain new and useful Improvements in Fire-Arms; and I do hereby declare the following to be a full, clear, and exact description of the same, reference being had to the accompanying drawings, forming a part of this specification, and to the figures and letters of reference marked thereon.

My present invention relates more especially to that class of breech-loading fire-arms known as "magazine-guns," and has for its main object the improvement of the loading and firing mechanism, whereby the weight, proportionally to the capacity of the gun, is diminished, the action rendered easy and positive, a multiplicity of parts, and more especially of springs, is avoided, the cartridge receiving and placing mechanism rendered efficient when used either as a breech or magazine loader with the magazine charged or empty and the lock or hammer rendered inoperative until the breech is properly closed ready for the discharge; and my invention consists in the several novel features of construction and combinations of parts, as hereinafter described, and more fully pointed out in the claims.

In the accompanying drawings, Figure 1 is a side elevation, partly in section, of a gun containing my present improvements. Fig. 2 is a side view of the feeding and firing mechanism, with the breech withdrawn ready to receive a cartridge from the magazine. Fig. 3 is a similar view showing the cartridge elevated. Fig. 4 is an enlarged view of the feeding mechanism, showing the detent in position to prevent the magazine-feed. Figs. 5, 6, and 7 illustrate certain details. Fig. 8 is a detail showing the manner of connecting the handlever to the link and cartridge lifter. Fig. 9 is a view of the front end of the gun.

Similar letters of reference in the several figures indicate like parts.

The gun is preferably constructed in three divisions or sections—first, the barrel and magazine, with means for securing the latter in position upon the former; second, the stock; and, third, the intermediate frame or

breech-piece carrying the loading and firing mechanism, and to which both the barrel and stock are detachably secured.

The breech-piece A is for convenience divided longitudinally, forming two parts or sections, A', similarly grooved and recessed, as hereinafter described, and firmly secured together by screws or other suitable contrivances. The straps or extensions a a, for attachment to the stock, are not divided, but are made integral with one of the sections.

The barrel B is provided on its under side with a series of loops or eyes, b, to receive and sustain the tubular magazine B', which latter is preferably composed of a sheet-metal tube slotted longitudinally, closed at one end by the screw cap or plug b', and carrying a spiral spring, b'', pressing upon a follower, b''', in one side of which is located a guide screw or pin, b'', working in the longitudinal slot of the tube. The magazine is retained in place, when inserted through the eyes b, by any suitable locking device, but preferably by the head of the cleaning-rod b'', the latter being passed through the eyes b and screwed into the block or head b', fastened permanently to the lower eye, b.

The sections A' of the breech-piece A are each provided with a lower flange, a'', two lugs, a'', a shoulder, a'', forming a grooved way, an upper shoulder, a'', a recess, a'', a curved bearing, a'', at the forward end, and a curved or semicircular extension, a'', at the top. It will be understood that several, if not all, of these recesses and flanges might, if desired, be made integral with or fastened to one of the sections, the other serving merely as a cap-plate; but, for obvious reasons, I prefer to construct them as shown. The two sections, when brought together, form an inclosing box or frame, within which the loading and firing mechanisms are contained and operated.

The barrel and magazine are attached or united to the breech-piece in the following manner, admitting of ready attachment and separation when desired: The opening or recess formed at the forward end of the breech-block between the bearings a' is of such shape and dimensions as to receive the lower loop or eye, b, or magazine B', and the block or head b'. The barrel B, when the block b' is

thus located, rests upon the shoulders a^5 , and its rear end projects under the semicircular extensions a^8 , which latter, meeting together, form an arch or socket within which the end 5 of the barrel is received. The parts thus arranged and disposed are fastened together and firmly secured in position by a screw or pin, b^{10} , passing through the section A' and the block b^7 , and by two set-screws, a^{10} —one on either side—passing through a bridge-piece, a^{11} , (fitting over and confining the extensions a^8) the extensions a^8 , and into suitable holes or recesses in the sides of the barrel. We now 10 have the barrel, magazine, breech-piece, and stock firmly and securely united and held together in such manner that they can readily be separated the one from the other, and the interior of the breech-piece laid open by the removal of one of the sections, and all this independent of the particular loading and firing 15 mechanism, the construction of which will next be described.

The distinguishing characteristics of this portion of my invention are, a perforated reciprocating carrier located beneath the barrel. 20 This carrier reciprocates upon the end of the magazine-barrel, hence is always kept charged so long as any cartridges remain within the magazine. It also carries the breech-block for closing the rear end of the barrel, and means for sustaining, inserting, and withdrawing the cartridges, the latter being transferred, 25 one at a time, by intermediate mechanism from the interior of the carrier into position against the face of the breech-block, where they are sustained by catches engaging the flanged head of the cartridge. These operations are automatically accomplished by a single movement 30 of a hand-lever, which latter, through connecting mechanism, simultaneously effects the locking of the carrier in position, the raising of the trigger, if desired, and the locking of the mainspring while the breech remains open, and its release only when the breech-block is 35 entirely closed. Moreover, the construction and arrangement of the transferring mechanism are such as that the magazine can be closed or the feed shut off at will, and the cartridges fed by hand, thus in a movement converting 40 the gun into a breech-loader or magazine-loader at will.

The mechanism shown for accomplishing these results is simple, efficient, and little liable to get out of order, and can be taken 45 apart, repaired, or the parts replaced without special skill or extraordinary expense. Resting on the shoulders a^4 , and sliding freely in the space or opening bounded on the top by the barrel B, and on either side by the sections A' of the breech-piece A, is a hollow or longitudinally-perforated block or carrier, C, preferably rectangular in cross-section, upon the rear upper face of which is formed or secured the breech-block C'. The rear end of 50 the stationary magazine B' projects within the carrier C, the latter being free to slide upon the former the full length of its stroke, where-

by the rear cartridge contained within the magazine will at all times be delivered and held in position within the carrier without liability of catching or being in any manner retarded. 70

Immediately in front of the breech-block C' is formed a slot or opening, c, in the carrier C, communicating with the central chamber 75 in the latter, and a corresponding slot, c', is formed in the lower portion of the carrier, extending to the extreme rear end thereof, for a purpose to be described. The breech-block C' is provided on either side with spring 80 fingers or catches C'', the inwardly-projecting ends whereof are substantially vertical and parallel, and on the upper forward edge of the breech-block is formed or attached a slightly-projecting flange or shoulder, c'''; or a spring 85 may be applied in lieu thereof, as shown in Fig. 6. The firing-pin c'', adapted for center or rim fire, as desired, works within a bracket formed within the breech-block C', and, together with the spring, is held in position by 90 means of a collar, c', screwed into the rear face of the said breech-block.

To the under side of the carrier C, near its forward end, is pivoted a link, D, the rear or free end of which is slotted for the reception 95 of a pin, d, carried by the forward end of the hand-lever D', the latter turning upon a screw, d', passing through the side pieces or sections, A'.

Turning upon a pin or screw, d'', is a bell-crank lever, D'', the upper arm, d'', being bifurcated, and its ends engaging shoulders d', formed on the under side of the carrier C, while the lower arm, d'', is rounded or cam-shaped on the end d'', and has a lug or pin, d'', on one side, and is recessed on the other side for the reception of a spring, D'', which encircles the pin d'', and has its free ends pressing, the one against the trigger and the other against the face of the arm d''. The action of 100 the spring D'' is to at all times press the toe of the trigger into engagement with the hammer, and the ends of the arm d'' against the under side of the carrier to engage the shoulders d' thereon. 105

Working between the bifurcated arms of the locking-lever D'', and within the slot in the carrier, is the cartridge-lifter D'', composed of a link, e, pivoted at one end on the pin d of the hand-lever D', and carrying on its rear or free end the slotted or bifurcated link e'. This link e' is constructed with a pointed and beveled or cam-shaped projection, e'', and two side plates or wings, e', embracing the end of the link e, the two being united by a pivot, e''. The upper faces of the wings e' are preferably beveled or concaved toward the center, forming a bearing to receive and sustain the cartridge, and the lower faces are inclined, as at e'', to facilitate their passage through the lever D'', and permit a light spring, e'', attached to the link e, to hold the front ends of the wings slightly elevated, the free end of said spring being arranged to bear against the lower edge of the 115 120 125 130

link e' , and thus retain the link e' in position. The hand or operating lever D' is provided with a shoulder, f , forward of its pivot, which, when the lever is closed, fits against the rear 5 end of the lower flanges, a^2 , thus closing the opening in the breech-piece. It is also provided with a projection or stud, f^2 , for engaging the cam-shaped end d^6 of the locking-lever D , and the lug or pin d^7 , as hereinafter described.

The operation of the feeding breech closing and locking mechanism above described is as follows: Starting with the breech-block closed, the hand or operating lever elevated, the cartridge-lifter down, and the locking-lever engaging the shoulders in the carrier, all as 15 shown in Fig. 1, when in this position, the projection f^2 on the hand-lever D' bears against the pin d^7 of the locking-lever D^2 , forward of its axis, thus securely retaining the points d^3 in position behind the shoulders d^4 of the carrier and preventing any backward motion of the latter; and to still further insure the locking of the carrier the link D is furnished with 20 a shoulder, f^3 , which, when said link is carried forward and downward by the hand-lever, engages a shoulder or stud, f^4 , on the breech-piece. The pin d on the hand-lever does not fit accurately the slot in the end of the link D , 25 said slot being made of such size and shape relative to the pin d and the two pivotal points as that when the hand-lever is elevated it shall hold the link in engagement with the shoulders f^3 , and at the same time permit the 30 said lever to be moved a sufficient distance to raise the link from the shoulder before exerting a pull upon the carrier, as well as to afford an 35 opportunity for withdrawing the points of the locking-lever. The cartridge-lifter D^3 , being 40 withdrawn by the hand-lever in closing, rests in the bifurcated end of the locking-lever in line with the opening in the carrier C , and with the forward ends of the wings slightly elevated. The rear cartridge delivered from 45 the magazine is forced backward, first depressing the forward ends of the wings, and then again elevating them as the head of the cartridge passes the rear ends of the said wings, and rests against shoulders f^6 in line 50 with but below the face of the breech-block C . The arm is now in condition for loading, for which purpose the hand-lever is drawn downward and forward. At the beginning of the movement of the hand-lever the projection f^2 55 is withdrawn from under the pin d^7 of the locking-lever D^2 , and, pressing upon the cam-shaped end d^6 of the arm d^5 , disengages the arm d^5 from the shoulders on the carrier C , and at the same time slightly elevates the rear end of the link 60 D . A further movement of the hand-lever draws back the carrier C , and with it the cartridge-lifter D^3 . As the forward end of the hand-lever rises and approaches the locking-lever D^2 , the cartridge-lifter D^3 is correspondingly elevated until the pointed and beveled 65 projection e^2 makes contact with the inclined wall g of a slot, g' , in the under side of the

carrier C , beneath the breech-block C' , which causes the link e' to rise vertically, carrying with it the cartridge which rests upon its surface, the forward ends of the side plates or wings, e^4 , closing the opening in the carrier and preventing the passage of the next succeeding cartridge.

In order to insure the proper action of the 75 lifter, it is desirable that it should have a more rapid movement than the carrier, to cause the point to make contact with the under side of the breech-block. This excess of motion is secured through the manner of attaching the 80 link D and end of the lifter to the operating-lever. A toggle is formed, the links of which, as the forward end of the lever is elevated, are brought more nearly in line, and as the other end of the lifter is not confined it is moved 85 correspondingly faster than the carrier. The cartridge resting upon the lifter D^3 is carried up through the slot e in the carrier, and the flanges on the head are forced under the ends of the spring fingers or catches C^2 . The hand-lever has now reached the limit of its outward 90 movement, and the cartridge is in position to be inserted within the barrel upon the return movement. The cartridge is now held and supported against the face of the breech-block 95 by the catches C^2 embracing its flanged head, and as the hand-lever is drawn back the cartridge-lifter moves downward and forward, to receive a fresh charge, while the breech-block carries the cartridge into gun-barrel in position to be fired. Just before the hand-lever is 100 closed and the breech-block seated against the end of the barrel, (which latter, by the by, has notches g^3 in each side, to receive the ends of the catches C^2 ,) the projection f^2 , coming in 105 contact with the cam-shaped end d^6 of the locking lever D^2 , forces the latter to yield and permit said projection f^2 to pass up against the pin d^7 , and immediately this is accomplished the link D is brought down by the closing of 110 the hand-lever until its shoulder interlocks with the shoulder f^4 . By this means the carrier C and breech-block C' are securely locked in place, and can only be drawn or forced back by the depression of the hand-lever. As 115 will be readily understood, the lifting into place of each succeeding cartridge will force out or detach the shell carried by the breech-block, and withdrawn from the barrel by the catches C^2 , which retain their hold upon the 120 flange so long as the cartridge remains within or in line with the barrel.

When it is desired to preserve the charge within the magazine and use the gun as a breech loader, a latch or catch, H , is pivoted 125 upon the link e , (shown in Fig. 4,) and held in either of two positions by a spring, h , bearing upon one of the flat faces h' . When the catch is turned back, as shown in dotted lines, it lies out of the way and does not interfere 130 with the free movement of the cartridge; but when the catch is turned forward, as shown in full lines, its end bears against the rear cartridge and bars its passage to the feeding and

lifting mechanism. The hammer I, which cooperates with the firing-pin to explode the shell, is preferably pivoted and operated at such distance below the breech-block as that 5 its striking end, when the hammer is cocked, shall be in line with the slot and opening in the carrier C, so that the latter, when retracted, may be moved over the end of the hammer, whereby the breech-piece is made shorter and 10 consequently more compact and lighter. When the carrier is retracted, it operates upon the hammer to raise it to the firing position, and in order to remove the pressure from the firing-pin and prevent the accidental discharge 15 of the cartridge, inclines *i* are located within the slot in the rear end of the carrier, which make contact with the shoulders *i'*, formed on the sides of the hammer.

In order to still further guard against the 20 accidental discharge of the piece, an arrangement has been devised for rendering inoperative the mainspring so long as the breech remains open. The mechanism for accomplishing this operation is applicable to many varieties of breech-loaders, magazine-guns, &c., and consists, essentially, of a link, K, suspended on the pivot K' of the tumbler K², against which latter the mainspring exerts its pressure. The link K is formed with a notch, k², 25 on one side, adapted to engage a pin, k³, and is held pressed against said pin by a spring, k⁴. The lower end of the link K is rounded and projects slightly through the breech-piece and in the path of the hand-lever. When the 30 lever controlling the opening and closing of the breech and the feeding or placing of the cartridges is brought back into place, the various parts are securely locked and held in position and the gun is in condition to be discharged; 35 but it may sometimes happen that the trigger will be operated before this point of safety is reached, and it is to prevent this premature discharge that the arrangement described has been made. When the hand or other operating 40 lever is removed from contact with the end of link K, the latter is caused to bear against the pin k³, and as soon as the hammer is elevated the hook or notch k² engages said pin k³, thus holding the mainspring down and re- 45 moving the pressure from the hammer to the pin. As soon, however, as the lever is brought back into position, but not before, it presses back the link K, thus disengaging the latter from the pin k³, releasing the mainspring, and 50 permitting the hammer to fall when the trigger is drawn.

I claim as my invention—

1. In combination with the detachable barrel provided with a block, b⁷, the breech-piece 55 provided with a recess to receive said block, and an arch or socket for the end of the barrel, the pin passing through the breech-piece and block b⁷, and the set-screws passing through the socket and into the barrel, substantially as described.

2. In combination with the barrel and its attached block b⁷, the longitudinally-divided

breech-piece having the recess for said block, the extensions a⁸, forming the socket for the end of the barrel, the overlying bridge-piece, the 70 set-screws for securing the same, and the pin for confining the block b⁷, substantially as described.

3. In combination with the magazine-tube extending within the breech-piece, the reciprocating carrier sliding in ways beneath the barrel and upon said magazine-tube, and a cartridge-lifter working through said carrier to raise and deliver the cartridges one at a time, substantially as described. 75

4. In combination with the barrel and the breech-frame to which it is attached, the hollow reciprocating carrier provided with the breech-block and mounted in ways beneath the barrel, the cartridge-lifter attached at one 85 end to the operating-lever and working through a slot in the said carrier, and the link connecting the carrier and said operating-lever, substantially as described.

5. In combination with the reciprocating 90 carrier, its attached link, and the operating-lever connected to the latter, the pivoted locking-lever provided with cam-shaped arm and locking-pin, the shoulders on the carrier for engaging the locking-lever, and the projection 95 on the operating-lever co-operating with the cam-shaped arm and locking-pin on the said locking-lever, substantially as described.

6. In combination with the reciprocating carrier, the link connected thereto and engaging shoulders on the frame, the operating-lever pivoted to said link and provided with a locking projection, and the locking-lever engaging shoulders on the carrier and provided with the cam and pin for co-operating with 105 the locking projections of the lever, substantially as described.

7. In combination with the sliding carrier, perforated and slotted, as described, for the reception and delivery of the cartridges, and the operating-lever connected to the carrier by a link, the link e, pivoted to the said lever and carrying the cartridge-lifter e', having the beveled end for engaging with the under side of the breech-block, substantially as described. 110 115

8. In combination with the slotted reciprocating carrier, its actuating-lever, and the bifurcated locking-lever, the cartridge-lifter carried by the actuating-lever and reciprocating between the arms of the locking-lever and into the slot in the carrier, substantially as described. 120

9. In combination with the operating-lever and the reciprocating carrier actuated thereby and provided with shoulders, as described, 125 the pivoted locking-lever having arms for engaging the said shoulders on the carrier and actuated by the operating-lever, the trigger, and the spring sustained upon the pivot of the locking-lever and bearing upon both the trigger and locking-lever, substantially as and for the purpose set forth.

10. The combination, with the reciprocating carrier provided with the slot and shoulders

at its rear end, the hammer pivoted below said carrier and provided with shoulders corresponding thereto, as described, the breech-block mounted upon the carrier, and the firing-pin extending through said breech, substantially as and for the purpose set forth.

11. In combination with the hammer and its spring, a link pivoted to the hammer, a pin upon the breech-frame to engage the link when the hammer is raised, and the breech-operating lever, a portion of the link projecting in the path traversed by the lever, whereby as the latter is closed it makes contact with said link and raises it from engagement with the pin, thereby releasing the hammer, substantially as and for the purpose set forth.

12. In combination with the hammer, the sliding carrier operating to raise the former, the link K, attached to the hammer and engaging a pin on the frame, and the operating-lever engaging the said link to move it out of engagement with the pin, and thus free the hammer, substantially as described.

13. In combination with the breech-piece, its attached barrel, and magazine-tube, the reciprocating carrier sliding in ways beneath the barrel, the breech-block fastened to said carrier and provided with the side catches, as described, and a cartridge-lifter pivoted to the operating-lever and working through a slot in said carrier to transfer the cartridges from the interior of said carrier into position in front of the breech-block, and with the flanges under the said side catches, the said carrier being also connected to the operating-lever, substantially as and for the purpose set forth.

14. In a magazine-gun, and as a means for preventing the transfer of the cartridges from the magazine by the cartridge-feeding mechanism when it is desired to load by hand, the combination, with automatic feeding mechanism, of a catch pivoted to the cartridge-lifter and adapted to be elevated to cut off the feed or turn down out of the way when used as a magazine-feeder, substantially as described.

15. In a magazine-gun such as described, and in combination with the breech piece or frame, to which are secured the stock, barrel, and magazine-tube, the sliding carrier perforated for the reception of the cartridge and carrying the breech-block, the cartridge-lifter working through such perforation, and the hammer and its operating mechanism located in the breech-frame below and to the rear of the said carrier, substantially as described.

16. In combination with the sliding carrier and the hand-lever having a pin, as described, the cartridge-lifter and the link pivoted to the carrier and connecting it to the carrier, both the said link and lifter being pivoted upon and actuated by the pin on the hand-lever, substantially as described.

17. In combination with the mainspring,

the hammer, and the operating hand-lever, the link pivoted to the hammer and provided with a hook, and the attaching pin secured to the breech-frame and engaging the said hook, substantially as described.

18. In combination with the hammer, its tumbler, and the mainspring applied to the latter, the hooked link pivoted to the hammer and the pin fastened to the breech-frame and engaging the hook on said link, when the hammer is raised, to hold the latter, substantially as described.

19. In combination with the sliding carrier, the operating-lever, the link pivotally connected to the said lever and to the sliding carrier and provided with a shoulder, f³, and a shoulder, f⁴, attached to the main frame, with which said shoulder f³ engages, when the lever is closed, to lock the carrier in position, substantially as described.

20. In combination with the reciprocating carrier, the operating-lever supported upon an axis below said carrier, a link, D, connecting the upper or forward end of the said lever to the sliding carrier at a point in advance of the axis of said lever, and a cartridge-lifter pivotally connected at its front end to the operating-lever, substantially as described.

21. In combination with the slotted reciprocating carrier provided with a longitudinal perforation communicating with the magazine, a lifter moving through the carrier to elevate the cartridges, and a catch mounted upon said lifter and in proximity to the perforation in the carrier through which the cartridges are fed, said catch being pivoted and provided with a sustaining-spring, substantially as and for the purpose set forth.

22. In combination with the vertically-reciprocating cartridge-lifter upon which the cartridges are delivered from the magazine, the catch pivotally supported within a slot in said lifter, and a sustaining-spring for holding the catch elevated above the surface of the lifter, to prevent the feeding of the cartridges, or depressed and within the slot, to permit the feeding, substantially as described.

23. In a breech-loading fire-arm, the combination, with the cartridge-feeding mechanism and a vertically-moving lifter for elevating the cartridges into position for insertion within the barrel, of a movable catch applied to the end of the lifter nearest the feeding-orifice, said catch operating, when elevated, to intercept the feeding of the cartridges upon the lifter, and when depressed to permit the free movement of the cartridge, substantially as described.
